UNITED STATES PATENT OFFICE.

ZACHARY T. HALL, OF PHILADELPHIA, PENNSYLVANIA.

DESIGN FOR A TRAY FOR PLAYING-CARDS.

SPECIFICATION forming part of Design No. 24,770, dated October 22, 1895.

Application filed February 23, 1895. Serial No. 539,482. Term of patent 14 years.

To all whom it may concern:

Be it known that I, ZACHARY T. HALL, a citizen of the United States, residing in the city and county of Philadelphia, State of Pennsylvania, have invented and produced a new and original Design for a Tray for Playing-Cards, of which the following is a specification, reference being had to the accompanying drawings.

The leading feature of my design for a tray for playing-cards is a mat formed of a central field, a pocket at each side of said field, and corner fields located diagonally to said central field and aside of said pockets.

Figure 1 represents a plan view of a tray

for playing-cards embodying my design. Fig. 2 represents a transverse section thereof.

In the drawings, A designates a tray consisting of a mat having the central field B, the pockets C at the sides of said field B, and the fields D at the corners of the mat located diagonally to the central field and aside of said pockets C.

What I claim is—

The design for a tray for playing cards, substantially as described and shown.

ZACHARY T. HALL.
